UNITED STATES PATENT OFFICE

171,505

AIR DIFFUSER FOR CEILINGS

Leo Krueger, Tucson, Ariz.

Application August 15, 1950, Serial No. 11,768

Term of patent 14 years

(Cl. D62—4)

To all whom it may concern:

Be it known that I, Leo Krueger, a citizen of the United States, residing at Tucson, in the county of Pima and State of Arizona, have invented a new, original, and ornamental Design for an Air Diffuser for Ceilings, of which the following is a specification, reference being had to the accompanying drawing, forming part hereof, in which:

Figure 1 is a perspective view of an air diffuser for ceilings, showing my new design.

Figure 2 is a view in side elevation thereof.

I claim:

The ornamental design for an air diffuser for ceilings, as shown.

LEO KRUEGER.
